SHIP

WINDING MECHANISM

Application filed June 8, 1928. Serial No. 283,819.

The present invention relates to thread winding mechanisms and more particularly to the winding and building up of bobbins evenly and perfectly.

In winding mechanisms as heretofore constructed, it has been the common practice to mount the winding mechanisms and the gain control devices upon a common vertical reciprocable bar, the arrangement being such that the gain movement is brought about by the feed cups striking the built up thread on the respective bobbins. These successive blows of the cup against the bobbins cause wear on the thread which in the case of silk thread either leaves periodic imperfections or actual breaks in the thread. Furthermore, such winding is a straight one and the completed cop or bobbin is objectionable because if subjected to rough handling the straight convolutions spill off of one end into a tangled mass. Another difficulty incident to these prior winding machines is that the gain cups must be manually shifted when the operator is catching up a thread and if not reset will drag over the face of the wound thread and produce worn places.

Some of the objects of the present invention are to provide an improved thread winding mechanism; to provide a thread winding mechanism wherein the gain control is non-reciprocable and is operated by contact with the thread without the customary impact operation; to provide a mechanism for efficiently performing a cross winding of a thread upon a bobbin; to provide means for rendering the gain mechanism of a thread winder inoperative while a bobbin is being removed and replaced; to provide a winding mechanism wherein bobbins of different sizes can be simultaneously wound upon the same machine; to provide a winding mechanism wherein delicate threads, such as rayon silk, can be wound into a perfect cop without the formation of worn or damaged portions; to provide a winding mechanism wherein the threads are so cross wound as to positively prevent slipping and end displacement; and to provide other improvements as will hereinafter appear.

In the accompanying drawings, Fig. 1 rep-

resents a front elevation of a winding mechanism embodying one form of the present invention; Fig. 2 represents a side elevation of the same; Fig. 3 represents a rear elevation of the same; Fig. 4 represents a section on line 4-4 of Fig. 3; Fig. 5 represents a detail of the traveller; Fig. 6 represents a detail of the movable arm for supporting the gain mechanism; and Fig. 7 represents a detail of base support member.

Referring to the drawings, one form of the present invention is illustrated in one unit of a multiple bobbin winding machine wherein a rigid cross bar 10 of the main frame of the machine serves as a stationary or fixed support, in the present instance, for the bobbins and gain control thread feeding devices, one bobbin and one control device only being shown for the purpose of describing the invention since the invention relates to one unit only and can be either a single or a multiple winding machine.

The bar 10 carries a bearing head 11, which is fixedly mounted on the bar 10, and forms a journal for the rotatable spindle 12 to which the bobbin supporting plate 13 is made fast. This plate 13 removably supports the bobbin 14 and transmits the desired constant rotary motion thereto. Motion is transmitted to the spindle 12 by a friction wheel 15 which rides upon the periphery of a driving friction wheel 16 fixed to rotate with the driving shaft 17 of the machine and the construction is such that the bobbin rotates at a predetermined constant speed at all times.

In order to disconnect the bobbin plate 13 from the rotating means so that the bobbin 14 can be removed and replaced, a hub or collar 18 is provided below the plate 13 and is arranged to seat upon a laterally movable cam face 20 formed on a part 21 pivoted to the head 11 and provided with a projecting handle 22 by which it can be swung to raise or lower the bobbin plate 13 so that the friction wheel 15 is out of or in contact with the driving wheel 16.

For the purpose of laying the thread 23 upon the bobbin 14, a thread laying-on guide 24 is provided which is located in close proximity to the side of the bobbin 14 and is car-

ried in the present instance by a wire 25 removably attached to one arm 26a of a bell crank 26, the other arm 26b of which supports a wire 27 terminating in an offset 28 located in the path of movement of a horizontally reciprocable operating arm 30. The bell crank 26 is mounted for rocking movement upon a pivot 31 projecting laterally from a lug 32 formed upon a horizontally 10 disposed traveller 33, while a spring 34 coiled about the pivot 31 exerts pressure upon the bell crank 26 in the proper direction to hold the offset 28 in contact with the vertically disposed operating arm 30. This arm 15 30 is fixed to a reciprocable rod 35 suitably guided by fixed parts of the machine frame and receives its motion by any suitable mechanical motion, such as a cam, crank or any other device capable of transmitting the desired 20 movement to give the required rise and fall motion to the thread laying-on guide 24 whereby the latter has a stroke of predetermined length. Thus the laying-on guide 24 is caused to travel in a path parallel to the axis of the bobbin 14 and this motion is preferably so proportioned with respect to the winding velocity of the bobbin as to cause the thread to be cross wound upon the bobbin and thereby give the desired overlapping 25 30 of the thread convolution which prevents break down of the wound cop. As here shown, the guide 24 is located parallel to the free end of the wire 25 and has its guide prongs 36 in close proximity to the wire in order to ensure the proper relation to prevent the thread from throwing out of the 35 guide.

In order to produce the required gain movement of the thread without reciprocation of the gain operating means, the traveller 33 is fixed to a sleeve 37 which serves as a journal for a cup or disc 38 and also rides freely upon a feed screw 40. This screw 40 is mounted upon a base 41 to stand parallel 40 to the axis of the bobbin 14 and spaced therefrom so that the bevelled side face 42 of the cup 38 will just overlap the path of the cop as it builds up and thus the contact of the rotating bobbin causes the cup 38 to have a 45 step by step turning movement. This turning movement of the cup 38 is transmitted to two oppositely disposed spring fingers 43 which ride in the groove of the thread of the feed screw 40 and hence cause the cup 38 to 50 travel along the screw 40 in the direction to compensate for the cop build up and thereby produce a cop of uniform diameter. The spring fingers 43 perform the function of a leader nut, advancing the cup in response to 55 the rotation of the cup about its sleeve 37. The base 41 is pivotally mounted upon a bracket 44 clamped to the frame rod 10 and is normally held by a spring 45 against a stop 46 so that the cup 38 is correctly positioned with respect to the bobbin 14. The

base 41 has a portion thereof in the path of movement of a side face cam 47 formed upon the cam part 21, and the relative positions of the parts is such that when the part 21 is swung to release the bobbin 14 its cam 47 will engage the base 41 and cause it to swing against the tension of the spring 45 in the direction to withdraw the edge of the cup 38 from the cop. 70

For guiding the traveller 33 and maintaining the parts associated with it in proper operative relation, a guide post 48 also extends upward from the base 41 and parallels the feed screw 40 so that the travel of the cup 38 is followed by the traveller 33 while the bell crank 26, guide 24 and offset 28 also move in the same direction but without interfering with the reciprocation of the bell crank 26 or varying its stroke. In other words the offset 28 is always in the path of the arm 30 and held pressed thereagainst by the action of the spring 34 though its position vertically considered will change in accordance with the feeding of the cup 38. Likewise the thread guide 24 will vary its position vertically but in every position its stroke will be the same. 75 80 85 90 95

In the operation of the winder, the traveller 33 is brought to its lowermost position so that the down stroke of the thread guide 24 terminates opposite to the bottom end of the bobbin and causes the thread to be laid from there upward. The up stroke of the thread guide 24 in this initial position terminates part way up the side of the bobbin 14 and the cup 38 is therefore set opposite to this upper end of the stroke. The machine is now started and the reciprocation of the rod 35 transmits motion to the arm 30 to oscillate the bell crank 26 alongside of the rotating bobbin 14 so that the guide 24 lays the thread upon the bobbin preferably with a cross wound effect. When the thread has wound the lower portion of the cop to the diameter where it comes into frictional contact with the bevelled face 42 of the cup 38 and in consequence the latter is given a partial turn which, by means of the fingers 43 and feed screw 40, simultaneously raises the cup 38 and the traveller 33 thereby bringing an unwound portion of the bobbin within the stroke of the guide 24 while maintaining the same length of stroke. Since the offset 28 is free to move upward along the operating arm 30, the reciprocation of the arm 30 transmits the same oscillation to the thread guide 24 irrespective of its position with relation to the bobbin and hence a uniform even winding takes place throughout the entire building up of the cop. When the winding of the bobbin has been completed, the handle 22 is manually swung to the left, as viewed in Fig. 1, and as a result the cam face 20 engages the hub 18 of the bobbin to lift this spindle 12 away from its driving means. 100 105 110 115 120 125 130

Following this lifting of the spindle 12, the continued swing of the part 21 brings the cam face 47 into contact with the base 41 to shift it and withdraw the cup 38 from above the winding and thus allow the wound cop and bobbin to be lifted off and an empty bobbin replaced.

Having thus described our invention, we claim:

- 10 A quick cross traverse winding machine comprising a bobbin support, a gain mechanism automatically operable in accordance with the build-up of a bobbin on said support, a reciprocable rod extending lengthwise of the machine, an operating arm fixed to said rod and having a length at least equal to the length of the bobbin to be wound, a bell-crank pivoted to said gain mechanism having an arm projecting into the path of
- 15 20 said operating arm, a thread guide carried by said bell-crank, and a spring holding said arm in contact with said operating arm.

Signed at Philadelphia, county of Philadelphia, State of Pennsylvania, this 7th day of June, 1928.
